FIG. 1

FIG. 5

FIG. 2

FIG. 3

FIG. 4

FIG. 6

FIG. 10

FIG. 7

FIG. 8

FIG. 9

FIG. 1 is a perspective view of a pouring cap for a jar showing my new design;

FIG. 2 is a side elevational view;

FIG. 3 is a rear elevational view looking from right to left at FIG. 2;

FIG. 4 is a top plan view;

FIG. 5 is a bottom plan view;

FIG. 6 is a perspective view of a pouring cap for a jar showing another form of my new design wherein the peripheral retaining ring is omitted;

FIG. 7 is a side elevational view;

FIG. 8 is an elevational view looking from right to left at FIG. 7;

FIG. 9 is a top plan view; and

FIG. 10 is a bottom plan view.

A portion of a jar is shown by means of broken lines in FIG. 2 for illustrative purposes only.

The dominant features of the design reside in those portions shown in solid lines.

I claim:

The ornamental design for a pouring cap for a jar, as shown and described.
